CLAIM

The ornamental design for a multi-compartmented cooking tray, as shown and described.

DESCRIPTION

FIG. 1 is a perspective top view of a multi-compartmented cooking tray showing my new design,
FIG. 2 is a top plan view thereof,
FIG. 3 is a bottom plan view thereof,
FIG. 4 is an elevational side view thereof, the opposite elevational side view being a mirror image; and,
FIG. 5 is an elevational end view thereof, the opposite elevational end view being a mirror image.

The broken lines in the drawings depict portions of the multi-compartmented cooking tray that form no part of the claimed design.
